Arthur H. Bartell, INVENTOR.

BY

Morell and Keeney. ATTORNEYS.

UNITED STATES PATENT OFFICE.

ARTHUR H. BARTELT, OF MILWAUKEE, WISCONSIN.

WRENCH.

Application filed August 6, 1920. Serial No. 401,582.

To all whom it may concern:

Be it known that I, ARTHUR H. BARTELT, a citizen of the United States, and resident of Milwaukee, in the county of Milwaukee, and State of Wisconsin, have invented new and useful Improvements in Wrenches, of which the following is a description, reference being had to the accompanying drawings, which are a part of this specification.

10 This invention relates to tools and more particularly to a compound wrench for use in making the adjustment of an ordinary form of tappet valve.

15 It is one of the objects of this invention to provide a tool for the purpose stated in which two wrenches are connectable to a holding member in sidewise spaced relation and provided with means for adjusting both wrenches angularly with respect to each

20 Another object of this invention is to provide a tool of the class described having a holding member for securing a pair of wrenches in sidewise spaced relation and 25 having means for securing one or more wrenches thereto when not in use to prevent the same from becoming detached and lost from the holding member.

25 A further object of this invention is to provide a tool of the class described having a holding member of angular shape having means on one arm thereof for adjustably fixedly connecting one wrench thereto and having means on the other end thereof for readily adjustably and fixedly securing another wrench thereto, the second wrench being movable with respect to the other at all angles.

30 A still further object of this invention is to provide a tool of the class described which will be readily adjustable and capable of withstanding the strain to which such a tool is subjected.

35 With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

55 Figure 1 is a side view of my improved wrench illustrating its use in adjusting a tappet valve, but a portion of the tappet valve being shown and parts thereof being broken away and in section;

60 Fig. 2 is a top view of my tool, a portion of the holding member being broken away;

65 Fig. 3 is a side view of my improved tool illustrating the manner of securing the various wrenches to the holding member when not in use.

70 Referring now more particularly to the accompanying drawing, in Fig. 1 is illustrated the adjustable part of a common form of tappet valve illustrating the manner in which my improved tool wrench is employed for adjusting the same. The tappet valve as illustrated consists of a valve member having a head (not shown) and stem 5, a bearing sleeve 6, a tappet member 7 slidably 75 and rotatably mounted in the sleeve and carrying a round flat head (not shown) for contact with a valve shaft cam (not shown), an adjusting screw 8 having threaded engagement with the upper end of the member 7 and provided with a nut head 9, and a lock nut 10 securing the screw in adjusted position. The upper end of the member 7 has opposite faces thereof flattened as at 11 for receiving a wrench to hold said member against turning movement when the screw 8 is being rotated to adjust the valve. Tappet valves of this type are set so that there will be a very slight clearance between the end of stem 5 and the head 9 of the screw 8 when the lowermost portion of the valve cam shaft is in contact with the head on the lower end of the member 7.

80 85 90 95 100 105 Heretofore it has been necessary for two persons to make the adjustment, each person having a wrench, one to engage the flat faces 11 of member 7 and the other to engage the head of screw 8, and then one of the persons uses another wrench to turn the lock nut 10 to secure the parts in adjusted position. With the present device, one person

holds both the adjusting screw 8 and member 7 with one hand while the nut 10 is tightened by a wrench 12 held in the other hand.

My improved device consists of a holding member 13 of angular shape substantially in the form of an L and having means for adjustably securing two wrenches 14 and 15 in sidewise spaced relation. The member 13 has the long arm 16 thereof slotted as at 17, through which slot the wrench 14 is insertable, and the upper portion 18 of the arm 16 is preferably of bendable spring material and the block 19 at the inner termination of the slot 17 is preferably of a thickness slightly less than that of the wrench 14.

This construction is such as to permit the free sliding movement of the wrench 14 within the slot 17 and at the same time provide means for rigidly securing the wrench 14 therein in any desired position, which means consists of a screw bolt 20 carried by the lower portion 21 of the member 13 and passing upwardly through the portion 18 and provided with a binding nut 22. With this construction, as will be readily seen, the nut 22 is screwed down to draw the end of portion 18 toward the portion 21, which will firmly bind or clamp the wrench 14 therebetween. The member 13 is preferably formed of but three pieces, the lower piece 21 being of heavy material and of substantially L shape, the block 19 secured to the portion 21 at the angle thereof, and the strip 18 which is secured to the block 19 and held 35 spaced from the long arm of the portion 21 to form the slot 17.

The short arm 23 of the holding member has pivotally secured thereto, and extending downwardly in opposite direction from the screw 20, a screw 24 upon which the wrench 15 is adjustably secured by projecting the screw between a threaded opening 25. This construction permits the wrench 14 to be adjustably spaced from the member 13, as will be readily apparent, and consequently adjustably spaced sidewise with respect to the wrench 15. All of the wrenches employed in connection with my improved tool are provided with a centrally threaded opening 25 to permit the securement of the same upon the screw 24 when not in use as best shown in Fig. 3, so that the wrenches will not become lost from the holder.

In use, the wrench 15 is secured upon the screw 24 in the proper relation with respect to the holding member and wrench 14 is then inserted through the slot 17 with the nut 22 loose upon the screw 20, when the wrench 14 is manipulated to obtain the proper adjustment of the adjusting screw 8. When the proper adjustment is obtained the nut 22 is screwed down to firmly bind the wrench 14 in the position it occupies when the adjustment is obtained. With the wrenches 14 and 15 thus firmly secured in their position

of adjustment, engaging the flat faces of the member 7 and the head 9 of the screw 8, the third wrench 12 is inserted therebetween to tighten the lock nut 10 and lock the screw 8 in its position of adjustment. 70

As will be readily apparent to those skilled in the art to which an invention of this character appertains, by reason of the wrenches 14 and 15 being capable of adjustment in sidewise spaced relation and of adjustment to various angles with respect to each other the tool may be readily manipulated to operate in the most efficient manner. 75

What I claim as my invention is:

1. A device of the class described comprising a slotted member through which a wrench is insertable and slideable, and turnable with relation to its work engaging end, and means carried by said member for pivotal engagement with a second wrench to 80 permit both wrenches to simultaneously engage nuts mounted on the same threaded member.

2. A device of the class described comprising a slotted member through which a wrench is insertable and turnable with relation to its work engaging end, and means carried by said member for pivotal engagement with a second wrench for holding the same in sidewise spaced relation and at an angle with respect to the work engaging end of the wrench inserted through the slot of said member. 90

3. A device of the class described comprising a pivoted holding member having a 100 slotted arm through which a wrench is insertable and turnable with relation to its work engaging end, a threaded shaft upon which a second wrench is securable to be held in sidewise spaced relation with respect to the first mentioned wrench, and means for locking the wrenches in various adjusted positions with respect to each other. 105

4. A device of the class described comprising a pivoted holding member having a 110 slotted arm through which a wrench is insertable at an angle, a threaded shaft upon which the second wrench is securable to be held in sidewise spaced relation with respect to the first mentioned wrench, and means for securing said wrenches in various angular positions of adjustment with respect to each other with their inner work engaging ends in alinement. 115

5. A device of the class described comprising a pivoted holding member having a slotted arm through which a wrench is insertable at an angle, a threaded shaft upon which the second wrench is securable to be held in sidewise spaced relation with respect to the first mentioned wrench, means for securing said wrenches in various angular positions of adjustment with respect to each other with their inner ends in alinement for engagement with the parts to be 120 125 130

held, and means for securing said wrenches in sidewise spaced relation.

6. A device of the class described comprising a holding member of substantially L shape, the long arm of the L being slotted to have a wrench inserted therethrough, means for securing the wrench inserted through said slot in any position of adjust-

ment, and means carried by the short arm of the L for adjustably securing a wrench thereto in sidewise spaced relation with respect to the first mentioned wrench. 10

In testimony whereof I affix my signature.

ARTHUR H. BARTELT.
